AUTOMATICALLY THREADING LOOM SHUTTLE.

Application filed September 28, 1928. Serial No. 309,053.

This invention relates to automatically threading loom shuttles wherein the shuttle is threaded during the loom operation, and is more particularly directed to thread tensioning means and thread lead for such shuttles to insure maintenance of proper tension upon the thread during weaving.

During normal weaving operations it is desirable to maintain a substantially constant tension upon the thread as it is delivered from the shuttle, in order that perfect cloth may be woven, and many attempts have heretofore been made to secure this desired result.

When the shuttle is completely threaded, the thread leads forwardly of the shuttle through a longitudinally extending thread passage and is delivered through the side delivery eye. Inasmuch as the shuttle is subjected to sudden shocks as it reaches the end of its pick, the thread is liable to be overthrown or loop frontwardly of the shuttle, and sometimes it will come out of the side delivery eye. Should the shuttle be picked from the non-replenishing side of the loom under the conditions above stated and the thread lead directly from the end of the filling carrier or bobbin backwardly to the cloth selvage, it will be broken.

One of the important features of the present invention consists of an automatically threading shuttle provided with double tensioning devices, one of which is mounted in the longitudinal thread passage adjacent the bobbin chamber, and hereinafter referred to as the "rear" tension device, and the other of which is mounted at the forward portion of the longitudinal passage, and hereinafter referred to as the "front" tension device, and during the normal weaving operation with the shuttle fully threaded, the thread is caused to pass through and under the control of both tensioning devices, thereby insuring a constant and uniform tension upon the thread during weaving. Associated with each of the tensioning devices is a thread guide, the guiding surface of which relative to both tensioning devices is below the top thereof, so that the thread is held in control of both tensioning devices during weaving.

Another important feature of the present invention consists of means disposed between the two tensioning devices to engage the thread when the shuttle becomes partially unthreaded and provide a lead for the thread under these conditions which will prevent

breakage and yet insure substantially the same constant tension upon the thread.

The invention and new combination of parts will best be made clear from the following description and the accompanying drawings of one good form thereof.

In the drawings:

Fig. 1 is a plan view of an automatically threading shuttle, showing more particularly the thread delivery end of the shuttle, and provided with the present invention;

Fig. 2 is a detached perspective detail of a threading block containing the present invention and showing the lead of the thread when the shuttle has become partially unthreaded;

Fig. 3 is an enlarged section on the line 3—3 of Fig. 1; and

Fig. 4 is a section through the threading block on the line 4—4 of Fig. 1, showing more particularly the rear tensioning device and the cover reaching partially over the top of said device.

The shuttle 1 is provided with the usual bobbin chamber 2 in which is mounted the filling carrier or bobbin 3 having the filling a wound thereon, and frontward of the bobbin chamber the shuttle is provided with an open longitudinal thread passage leading to the side delivery eye 4. In the present instance of the invention, the longitudinal thread passage 5 is formed in a threading block 6 which may be appropriately secured in the usual threading block chamber of the shuttle by means of a bolt 7 which passes through an opening 8 in the threading block.

Mounted in the longitudinal thread passage is the rear thread tensioning device which, as shown in the present instance, is of the spring clamp type. The rear tensioning device consists of two plates 9 and 10, Fig. 4, between which the thread passes as it is delivered from the shuttle, and each of the tensioning members 9 and 10 may be appropriately subjected to the clamping action of the springs 11 and 12 whereby the two clamping members are held in closed or clamping position. One of the springs, as 12, in the present instance, may be adjusted to exert more or less tension upon its associated clamping member 10 by means of an adjusting screw 13, one end of which bears against the spring 12, and the other end of which extends to the exterior of the shuttle, whereby it may be adjusted to exert the de-

sired tensioning effect upon the associated clamping member 10. The upper end of each of the clamping members 9 and 10 is flared outward, as indicated at 14 and 15, Fig. 4, and the outer portions thereof extend into openings 16 and 17 formed in the walls of the threading block 6. The two clamping members 9 and 10, as shown, are mounted upon a cross-pin 18 extending transversely of the threading block, which affords a support for the clamping members in their position adjacent the entrance to the longitudinal thread passage and bobbin chamber.

At the forward or front end of the longitudinal thread passage 5 is the front spring tension device which is preferably positioned as the bridge delivering end of the thread passage. The front spring clamp tensioning device may be variously contrived, but is herein shown as comprising a fixed cylindrical member 19 and a spring-actuated clamping member 20, both of which may be mounted upon a suitable support, as, for instance, the threaded bolt 21, Fig. 3. The fixed clamping member 19 is preferably mounted in a suitable recess 22 formed in the front wall 23 of the threading block, while the spring-actuated clamping member 20 is oppositely disposed upon the threaded bolt 21 and is provided with a recess 24 in which may be seated a spring 25 bearing against the head 26 of the threaded bolt and exerting an inward stress or compressive action against the tensioning member 20.

As indicated more clearly in Figs. 1 and 2, the contacting surfaces of the two clamping members 19 and 20 are so disposed that the thread passing between the clamping members may be deflected to one side of the thread

passage towards the side delivery eye. From the construction thus far described it will be apparent that the present invention provides two spring-clamped tensioning members, one adjacent the entrance to the longitudinal thread passage, and the other adjacent the forward or front end portion of the thread passage, and during the weaving operation the thread passes through and is under control of both of the tensioning devices, which may be adjusted to exert the desired tension upon the thread.

Associated with each of the two tensioning devices is a thread guide whose thread-engaging surface is below the top portions of the two tensioning devices.

The thread guide adjacent the rear spring tensioning device is formed by a laterally and downwardly extending projection or toe 27, as more clearly indicated in Fig. 2, and the guiding surface 28 which is curved upwardly at the inner portion of the projection 27, is below the top of the rear tensioning device composed of the tensioning members 9 and 10, with the result that during weaving operations the thread being unwound from

the filling carrier or bobbin will be held sufficiently low relative to the rear spring tensioning device to insure its proper engagement between the two tensioning members thereof.

The thread guide for the front tensioning member, shown more clearly in Fig. 1, is formed on or is part of the threading block frontward and at the side of the front tensioning device, and consists of a guide member 29 the guiding surface of which is below the top of the front tensioning device and under which the thread passes on its way to the side delivery eye 4.

During normal weaving operations when the shuttle is fully threaded it will be apparent that the double tension, one member of which is adjacent the entrance to the longitudinal thread passage and the other of which is adjacent the exit of the thread passage, will both engage the thread and subject it to the uniform action as described, by the spring action of the spring clamping members of the tension devices.

Extending downwardly well into the longitudinal thread passage 5 from the back wall 30 of the longitudinal passage between the rear and front spring tension devices is a hook 31, the lower end portion 32 of which reaches forward towards the front spring tension device, and should the thread *a* be thrown from the side delivery eye during the weaving operation, it will be caught by the hook 31 and given a lead to prevent thread breakage as the shuttle is picked.

At this time it is desirable that the thread lead be such as to insure that the thread delivered from the thread carrier or bobbin 3 be maintained in control of the rear tensioning device, and to this end the lead portion 33 of the hook 31 about which the thread passes under the conditions above noted, is located well down in the longitudinal thread passage below the top of the rear tensioning device, thereby insuring in connection with the thread lead at the entrance to the longitudinal passage that the thread will be given tension by the rear tensioning device.

Extending from the top portion of the front wall 23 of the thread passage is a cover 34 which reaches laterally over the top of the rear tensioning device, as indicated more clearly in Figs. 1, 2 and 4. The cover 34 has the forwardly extending rounded edge 35 and adjacent the entrance to the longitudinal thread passage it is curved outwardly again, as at 36, to form a recess 37 between the projection 27 and the top of the cover, the result being that when the shuttle is partially threaded; that is, the thread has been thrown out of the side delivery eye and leads backwardly about the lead portion 33 of the hook 31, the portion of the thread *a* leading from the filling carrier or bobbin will pass through the rear spring tension-clamp about the lead

of the hook 31 and then backwardly towards the cloth selvage, as indicated at a' , Fig. 2, and engage under the cover 34, the down-turned edge of which at 35 will engage the 5 backward extending portion a' of the thread a to impart to the thread an additional friction or tension, thus compensating for the lost frictional tension previously exerted by the front spring tensioning device.

10 From the construction thus far described it will be apparent that during normal weaving operations when the shuttle is fully threaded, the double tension devices, one at the rear and the other at the front of the 15 thread passage, will act upon the thread to insure the desired tension, and when the thread is thrown out of the side delivery eye and is thus partially unthreaded it will extend around the lead portion 33 of the hook 20 31 in the longitudinal thread passage below the top of the rear tension device and then be drawn under the edge of the cover 35 to secure practically the same amount of tension or friction upon the thread as it had during 25 normal weaving operations.

What is claimed is:

1. An automatically threading loom shuttle having a bobbin chamber, a longitudinal thread passage having an open top through 30 which the thread automatically passes on the first pick of the shuttle following replenishment and side delivery eye, a rear spring clamp tension device mounted in the longitudinal thread passage adjacent the bobbin 35 chamber, and a bridge formed as a front spring clamp tension device mounted in the longitudinal thread passage at the forward or exit end thereof and through which the thread passes downwardly to the side delivery eye when the shuttle is completely threaded that the double spring tensions may act upon the thread and insure tension thereon during weaving.

2. An automatically threading loom shuttle having a bobbin chamber, a longitudinal thread passage into which the thread passes automatically on the first pick of the shuttle following replenishment and side delivery eye, a rear spring clamp tension device mounted at the entrance to the longitudinal thread passage adjacent the bobbin chamber, and a bridge constituted as a front spring clamp tension device mounted in the longitudinal thread passage at the forward or exit end 50 thereof, a thread guide below the front spring clamp tension device adjacent the exit end of the longitudinal thread passage to deflect the thread downwardly through and into control of the tension device during weaving.

60 3. An automatically threading loom shuttle having a bobbin chamber, a longitudinal thread passage and side delivery eye, a rear spring clamp tension device mounted in the longitudinal thread passage at the entrance 65 thereto adjacent the bobbin chamber, a thread

guide extending transversely of the longitudinal thread passage between the rear spring clamp tension device and the bobbin chamber to depress the thread into control of the said tension device, and a bridge constituted as 70 a front spring clamp tension device mounted in the longitudinal thread passage at the forward or exit end thereof adjacent the side delivery eye that the double spring tensions may act upon the thread and insure tension thereon during weaving.

4. An automatically threading loom shuttle having a bobbin chamber, a longitudinal thread passage and side delivery eye, a rear spring clamp tension device between the 80 members of which the thread passes at the entrance to the longitudinal thread passage, a thread guide transversely of the entrance to the thread passage having its thread guiding portion below the top of the rear spring 85 clamp tension device to maintain the thread in control of said tension device during weaving, and a front spring clamp tension device at the exit end of the longitudinal thread passage that the double spring tensions may 90 act upon the thread during weaving and insure proper tension.

5. An automatically threading loom shuttle having a bobbin chamber, a longitudinal thread passage and side delivery eye, 95 a rear spring clamp tension device between the members of which the thread passes at the entrance to the longitudinal thread passage, a thread guide transversely of the entrance to the thread passage having its thread guiding portion below the top of the spring clamp tension device to maintain the thread in control of said tension device during weaving, and a front spring clamp tension device at the exit end of the longitudinal thread passage, 100 105 and a thread guide below the second spring clamp tension device to maintain the thread in control of said front tension device and direct it to the side delivery eye that the double spring tensions may act upon the 110 thread during weaving and insure proper tension.

6. An automatically threading loom shuttle having a side delivery eye and a threading block provided with a longitudinal 115 thread passage, a rear spring clamp tension device between the members of which the thread passes adjacent the entrance to the longitudinal thread passage, a front spring clamp tension device adjacent the exit end 120 of the longitudinally thread passage forming the bridge, and thread guides having their thread guiding portions below the thread clamping portion of the adjacent spring clamp tension device to maintain the thread in control of said tension devices as the thread is delivered from the shuttle during weaving.

7. An automatically threading loom shuttle having a bobbin chamber, a longitudinal thread passage and side delivery eye, a 130

5 rear spring clamp tension device mounted in the longitudinal thread passage adjacent the bobbin chamber, and between the members of which the thread passes, and a bridge at the front terminal portion of the thread passage constituted as a spring clamp tension device comprising two members having their abutting faces between which the thread passes at the side of the thread passage adjacent the side delivery eye that the thread 10 may be subjected to tension by each of the spring tension devices during weaving.

8. An automatically threading loom shuttle having a bobbin chamber, a longitudinal thread passage and side delivery eye, a rear spring clamp tension device mounted in the longitudinal thread passage adjacent the bobbin chamber, and between the members of which the thread passes and a front spring 15 clamp tension device forming the bridge in the longitudinal thread passage at the forward end thereof and comprising two members having their tensioning faces at the side of the thread passage adjacent the side delivery eye that the double spring tensions may act upon the thread and insure tension thereon during weaving, and a thread engaging hook reaching forward from the back wall of the thread passage between the two tension 20 devices to guide the thread in case it fails to pass through the front tension device and side delivery eye as the shuttle is picked.

9. An automatically threading loom shuttle having a bobbin chamber, a longitudinal thread passage and side delivery eye, a rear spring clamp tension device mounted in the longitudinal thread passage adjacent the bobbin chamber, and a front spring clamp tension device mounted in the longitudinal 25 thread passage at the forward or exit end thereof and constituting the bridge adjacent the side delivery eye that the double spring tensions may act upon the thread and insure tension thereon during weaving, a thread engaging hook in the longitudinal passage between the two tension devices to guide the 30

thread in case it fails to be delivered through the front tension device and side delivery eye, and a cover reaching across part of the rear tension device to engage above the thread 50 when it is guided by the hook between the two tension devices as the shuttle is picked.

10. An automatically threading loom shuttle having a bobbin chamber, a longitudinal thread passage and side delivery eye, a rear spring clamp tension device mounted in the longitudinal thread passage adjacent the bobbin chamber, and a front spring clamp tension device mounted in the longitudinal thread passage at the forward or exit end 55 thereof adjacent the side delivery eye that the double spring tensions may act upon the thread and insure tension thereon during weaving, a thread engaging hook in the longitudinal passage between the two tension devices to guide the thread in case it fails to be delivered through the front tension device and side delivery eye, and a cover reaching from the front wall of the thread passage 60 across part of the rear tension device and under which the thread passes when it is guided by the hook between the two tension devices as the shuttle is picked.

11. An automatically threading shuttle having a side delivery eye and threading block provided with a longitudinal thread passage, a rear spring tension device and a front spring tension device constituting a double tension for the thread during normal weaving operations, a cover reaching from the front wall of the thread passage part way across and above the rear spring tension device, a hook reaching forward in the thread 75 passage between the tension devices and having its thread guiding portion lower than the 80 cover that the thread may be guided below the cover should it fail to be delivered through the front spring tension device and side delivery eye when the shuttle is picked.

In testimony whereof, I have signed my 90 name to this specification.

HARRY A. DAVIS.
